UNITED STATES PATENT OFFICE.

HANS T. SCHEIDACKER, OF BROOKLYN, NEW YORK, ASSIGNOR TO HUDSON BRASS WORKS, INC., OF NEW YORK, N. Y., A CORPORATION OF NEW YORK.

DESIGN FOR AN ARM FOR BRIDGE LAMPS.

Application filed November 6, 1928. Serial No. 28,777. Term of patent 3½ years.

To all whom it may concern:

Be it known that I, HANS T. SCHEIDACKER, a citizen of the German Republic, residing at Brooklyn, in the county of Kings and State of New York, have invented a new, original, and ornamental Design for an Arm for Bridge Lamps, of which the following is a specification, reference being had to the accompanying drawings, forming part thereof.

Fig. 1 is a plan view of the arm; and Fig. 2 is an elevational view of the same.

I claim:

The ornamental design for an arm for bridge lamps, as shown.

In testimony whereof I have hereunto set my hand.

HANS T. SCHEIDACKER.
